UNITED STATES PATENT OFFICE.

ROSS HICKERNELL, OF WARREN, OHIO.

SOLO TRUMPET.

Application filed May 24, 1922. Serial No. 563,361.

To all whom it may concern:

Be it known that I, Ross HICKERNELL, a citizen of the United States, residing at Warren, in the county of Trumbull and State of Ohio, have invented certain new and useful Improvements in Solo Trumpets, of which the following is a specification.

The trumpet has heretofore been used exclusively as an orchestral instrument, speaking only when the strident quality of tone is desired, and not as a solo instrument. Its tone is hard, inflexible, unsympathetic and even blatant. It lacks that mellowness, flexibility and broader tone which adapts the cornet to solo work. Yet the latter is not an ideal solo instrument, either from a musical standpoint, because of its lack of brilliancy; or from an artistic standpoint, because of its general appearance.

Originally the trumpet was an eight foot C principle, twice as long as the present cornet and trumpet in C, and produced sixteen harmonics in its practical register, with a compass extending one octave deeper than the cornet. There was thus a distinct difference. The trumpet had a refined noble quality of tone, extremely rich and flexible, while the cornet, when first produced, was quite the contrary and at variance with the trumpet quality. It had but eight harmonics and was quite harsh and unrefined in comparison with the trumpet. However, because of its shorter tube and consequent greater separation of harmonics, for certain popular styles of composition, it could be played upon with more assurance and freedom than upon the eight foot trumpet. As a consequence, the cornet grew rapidly in popularity and favor, the old eight foot trumpet became obsolete and the four foot principle was adopted for both the cornet and the trumpet. This transition in the case of the trumpet resulted in the creation of the modern four foot trumpet with a voice so harsh and unmusical as to be unfit for the class of work for which the cornet was invented, to wit:—the solo, and it has therefore for many years been relegated to the orchestra.

The trumpet from time immemorial has been regarded as the classic wind instrument, full of grace and charm and in tone it is naturally the soprano of the brasses; yet as now constructed it stands apart and distinct from the other members of the brass family of instruments. The trom-

bone and tuba are in agreement as to tonal quality, each having a clear, free full tone throughout its entire register. On the other hand, the modern trumpet does not even agree with itself in its several registers, the lower register being foggy, the middle register being inclined to break and choke, and the upper register alone being clear but also coarse; and producing no fundamentals.

The object of my invention is to produce a trumpet for solo work, having a quality of tone that is clear, full, resonant and brilliant throughout its register from its lowest to its highest tone, and without any of the harsh, shallow, inflexible, coarse and blatant qualities of tone which heretofore characterized the modern trumpet; and to produce all fundamental tones.

In the following description, I shall refer to the accompanying drawings, in which Figure 1 is a side view of a trumpet embodying my invention and Figure 2 is a sectional view on the line 2—2 of Fig. 1.

The general arrangement of parts is the same as usual, including the valve cylinders 3, which contain the usual valves controlled by the fingering keys 4, for changing the air passages through the several crook-tubes 5, 6, 7 in producing the different tones, in the manner well understood and requires no explanation.

In trumpets, as heretofore constructed, the tubes forming the air ducts or passages from the mouth piece to the beginning of the bell tube have been of uniform diameter, with mouth-pipe of large bore, and bell of proportionately small diameter. The tones which are produced upon these instruments have the undesirable qualities above described. For the purpose of discovering the defects which are responsible for the production of these undesirable qualities, I have conducted a large number of experiments extending over a long period of time. I have discovered that the objections specified can be overcome and the desirable qualities can be produced by changing the construction of certain portions of the instrument while retaining the same arrangement of parts. The essential features of my invention or discovery consist in constructing the mouth-pipe or tube, and the curved end tubes which respectively connect the mouth-pipe with the intermediate valve mechanism and the latter with the bell-tube,

of small and tapering construction, properly graduated; the bore of the tube in these portions increasing gradually in diameter by distinct mathematical ratios in the direction of travel of the air column. I have determined that the intermediate tubes constituting the valve-controlled passages by which the length of the air column is varied, should remain of uniform diameter or bore in order to effect the desired result.

In constructing the trumpet in accordance with my invention, the mouth-pipe 10 is made smaller than prior instruments of this type where it joins the mouth piece 11 and gradually increases progressively in diameter to the end of this tube, indicated at *b*, nine inches, at the ratio of three to four. The end U-tube 12 is formed with a gradually increasing diameter from the point *c* to the point *d*, three inches; at the ratio of eight to nine. The connecting tubes 8 and 9 should be of uniform size; and the crook-tubes 5, 6, and 7 are also of uniform diameter. The bell tube 14 beginning at the point *e* increases progressively in diameter, more gradually around the curved end portion, seven inches, at the ratio of four to five and more rapidly in the straight portion leading to the bell $14\frac{1}{2}$, 12 inches, at the ratio of one to two and from $14\frac{1}{2}$ to 15—four inches, at the ratio one to two. By the construction described, the vibrating air column is permitted to expand continuously and progressively as it passes through the gradually enlarging bore of the mouth-pipe 10 and again as it passes through the gradually increasing bore of the end U-tube 12 leading to the intermediate valve controlled crook-tubes; and continuing therefrom the air column is permitted to expand continuously and in larger form from the initial curved end of the bell-tube until it emerges from the bell.

I have found that it is important that the vibrating air column should be formed much smaller at the beginning than heretofore and to expand gradually after leaving the mouth piece the limited length before mentioned, and that it is essential also that this air column should be permitted to expand as it passes around the curved ends of the tubes, that is, through the U-tube 12 and the initial curved end of the bell pipe 14 and that it should increase more rapidly from this point to $14\frac{1}{2}$, and with extreme rapidity from this point to end of bell 15. I have also found that the intermediate valve-controlled crook-tubes should maintain the air column of uniform size at these

sections and of an internal diameter corresponding with the exit end *d* of the U-tube 12. In fact, it is by making these intermediate valve controlled tubes which regulate the varying length of the air passage of the instrument of uniform bore between the conical sections, that I am able to maintain and preserve the superior tonal qualities and which would be destroyed by the manipulation of the controlling valves, if said intermediate crook-tubes and connecting parts were not of uniform diameter.

I claim:

1. A solo trumpet, comprising a small mouth-pipe progressively increasing in diameter at the ratio of three to four in a length of nine inches, intermediate mechanism for controlling the length of the vibrating air column, having valve-controlled crook-tubes of uniform diameter, a U-tube of progressively increasing diameter interposed between the mouth-pipe and said intermediate mechanism, and a bell-tube connected to said intermediate mechanism and terminating in a large bell, said bell-tube having a curved end portion and a straight portion terminating in the bell, the straight portion being graduated at the ratio of one to two in a length of twelve inches.

2. In a solo trumpet as set forth in claim 1, said curved end portion of the bell-tube being graduated at the ratio of four to five in a length of seven inches.

3. A solo trumpet, comprising a small mouth-pipe progressively increasing in diameter at the ratio of three to four in a length of nine inches, intermediate mechanism for controlling the length of the vibrating air column, having valve-controlled crook-tubes of uniform diameter, a U-tube of progressively increasing diameter interposed between the mouth-pipe and said intermediate mechanism, said U-tube being graduated at the ratio of eight to nine in a length of three inches, and a bell-tube connected to said intermediate mechanism and terminating in a large bell, said bell-tube having a curved end portion and a straight portion leading to the bell, the curved end portion being graduated at the ratio of four to five in a length of seven inches and the straight portion being graduated at the ratio of one to two in a length of twelve inches and the bell being graduated at the ratio of one to two in a length of four inches.

In testimony whereof I affix my signature.

ROSS HICKERNELL.
